UNITED STATES PATENT OFFICE.

MAURICE SIMON, OF ST. LOUIS, MISSOURI, ASSIGNOR TO FIRE TOP MANUFACTURING COMPANY, OF ST. LOUIS, MISSOURI, A COPARTNERSHIP.

LUMINOUS SPINNING-TOP.

1,319,123.

Specification of Letters Patent. Patented Oct. 21, 1919.

Application filed April 28, 1919. Serial No. 293,350.

To all whom it may concern:

Be it known that I, MAURICE SIMON, a citizen of the United States, residing at the city of St. Louis and State of Missouri, have 5 invented a new and useful Luminous Spinning-Top, of which the following is a specification.

My invention relates to improvements in toy spinning-tops and consists in the novel 10 design and construction hereinafter disclosed.

An object of my invention is to provide a toy spinning-top of such a character as will glow luminously when spun in a prop- 15 erly darkened room or elsewhere, and thus tend to constitute a form of entertainment.

I attain this object by the device illus- 20 trated in the accompanying drawing, in which—

Figure 1 represents a vertical section of the device taken on the line 1—1 of Fig. 2.

Fig. 2 is a top plan view of the device.

Similar numerals refer to similar parts throughout the several views.

In the embodiment of the invention illus- 25 trated, the luminous spinning-top is shown to comprise a spindle 1 and an annular disk 2 mounted concentrically on said spindle 1 and formed preferably integral therewith, 30 the entire device being formed or molded from a transparent rigid material, preferably glass or celluloid. The portion of said spindle below the disk develops or tapers substantially to a blunt point 3 upon 35 which the device is spun. The portion above the disk constitutes the stem 4 by which the top is supported between the thumb and finger and actuated.

A preferably circular pocket or recess 5 40 is formed in the under face of said annular disk 2 substantially at the periphery thereof. A layer or coat 6 of self-luminous material, preferably of a radium composition in the form of a paint or paste, is disposed 45 within said pocket or recess 5 in the manner illustrated in Fig. 1. The open construction

indicated tends to facilitate the application of the said self-luminous material with a brush or any other suitable instrument.

In practice, the device is supported by the 50 stem 4 between the thumb and finger and given a sudden twirl thereby, thus causing the luminous top to spin upon a suitable flat surface in the usual manner. The de- 55 vice is primarily adapted to be operated in a substantially darkened room or other place from which light is absent, the self-lumi- 60 nous material disposed therein emitting a luminous glow clearly visible through the transparent disk and having substantially 65 the appearance of a luminous circular spot. Upon operation, the rapid spinning motion or action of the top tends to transform the luminous top into a continuous luminous ring, which result constitutes the entertain- 70 ing feature of the invention.

I am aware that various changes may be made in the design and structure of the device without departing from the spirit and scope of my invention. I do not limit myself therefore, to the exact detail shown and described, but what I claim and desire to 75 secure by Letters Patent is:—

1. As a new article of manufacture, a luminous spinning-top comprising a spindle, 75 a transparent disk mounted concentrically on said spindle, a pocket or recess formed in said disk, and self-luminous material disposed in said pocket or recess.

2. As a new article of manufacture, a lu- 80 minous spinning-top comprising a spindle, a transparent disk mounted concentrically on said spindle, a pocket or recess in the under face of said disk, and self-luminous material disposed in said pocket or recess. 85

3. As a new article of manufacture, a lu- 90 minous spinning-top comprising a spindle, a disk mounted concentrically on said spindle, and self-luminous material disposed at a point on said disk substantially at the periphery thereof.

MAURICE SIMON.
